CLAIM

The ornamental design for a display screen with transitional graphical user interface, as shown and described.

DESCRIPTION

Reproductions 1.1 to 1.6 are front views showing a display screen with transitional graphical user interface.

The appearance of the transitional image sequentially transitions between the images shown in Reproductions 1.1-1.6. The process or period in which one image transitions to another image forms no part of the claimed design.

(Continued)

XXXXX XXXXXXXXXX XXXX
XXXX XXXXXX

The broken line showing of the transitional graphical user interface is included for the purpose of illustrating portions of the article and forms no part of the claimed design.
